UNITED STATES PATENT OFFICE.

AUGUST S. LIZAK, OF CHICAGO, ILLINOIS, ASSIGNOR TO KENTOWSKI & COMPANY, OF CHICAGO, ILLINOIS, A COPARTNERSHIP CONSISTING OF M. E. KENTOWSKI, T. E. WINIARSKI, AND AUGUST S. LIZAK.

WRENCH.

1,385,180.

Specification of Letters Patent. Patented July 19, 1921.

Application filed October 25, 1920. Serial No. 419,279.

To all whom it may concern:

Be it known that I, AUGUST S. LIZAK, a citizen of the United States, residing at Chicago, in the county of Cook and State of Illinois, have invented certain new and useful Improvements in Wrenches, of which the following is a specification.

This invention relates to a wrench adapted for the gripping of polygonal or curved surfaces, and is characterized by a number of features of improvement which will more clearly hereinafter appear. More particularly this wrench embodies strength without undue weight, and may be adjusted with facility through a simple assembly of parts that are inexpensive to construct. A suggestive embodiment of my invention is illustrated in the accompanying drawing wherein—

20 Figure 1 is a side elevation of the wrench; Fig. 2 is a fragmentary enlarged sectional view taken on line 2—2 of Fig. 3;

25 Fig. 3 is a transverse section taken on line 3—3 of Fig. 2; and

Fig. 4 is a detail in elevation looking upon the parts indicated by the line 4—4 of Fig. 2.

The handle A of my wrench may be formed in the usual manner and is provided at one end with a head 5 on which is mounted a fixed jaw 6 serrated in the usual manner.

30 The sides of the handle adjacent this jaw are recessed to provide a neck 7 upon which is secured a U-shaped frame B formed with parallel sides 8 and a back or connecting wall 9. This frame is pivotally mounted upon the wrench as by means of a pin 10 so as to have capacity for rocking to a slight extent, shoulders 11 and 12 at opposite ends of the neck 7 co-operating with the

40 walls of the frame to limit its movements. Extending laterally from the handle adjacent the shoulder 12 are a pair of lugs 13 in spaced relation, as best shown in Fig. 4.

45 Mounted within the frame is a slidable jaw C having the rear edge of its shank 14 provided with ratchet teeth 15 adapted to co-operate with similarly formed teeth 16 which are formed on the inner side of the frame back 9. Extending laterally from the shank of this movable jaw at one end is a head 17 serrated as at 18 to enhance its gripping effect as is usual with such de-

vices, and at the other end I have provided an outstanding lug 19 which serves as a stop to prevent the jaw from sliding completely out of the frame.

With a wrench constructed in accordance with the preceding description, I combine certain elements which cooperate in maintaining the slidable jaw in a fixed position of adjustment. For this purpose, use is made of a spring 20 which may be coiled to seat within a socket 21 formed in the neck 7, this spring receiving a stud 22 which is pressed against one end 23 of a leaf spring 24 whose opposite end is secured to the handle as by means of a screw 24. The effect of this spring is to maintain the slidable jaw away from the handle and in constant engagement with the back of the frame, so that the two sets of ratchet teeth may co-operate to prevent the jaw C from being moved outwardly relative to the fixed jaw. To adjust the jaw C to another position, it is necessary that the spring D be depressed against the tension of the spring 20, and for this purpose means are provided as follows: A pin 25 is arranged transversely between the walls 8 of the frame in spaced relation to the spring D, and arranged to enter between this pin and spring is the foot 30 of a wedge E that is slotted as at 31 to receive through its body a pin 32 which extends between the two lugs 13. A spring 33 coiled around the wedge presents one end to the pin 32 and its other end against a head 34 provided on the wedge, the tendency being to hold the wedge retracted so that its foot 30 may not interfere with the action of the spring D in holding the slidable jaw in engagement with the frame back.

From the foregoing description, it will be noted that I have provided a wrench wherein the two jaws may be held in a relatively fixed position of adjustment through the medium of ratchet teeth, two springs being employed to assist in this operation. To shift the movable jaw into another position of adjustment, it is not necessary to exert lateral pressure upon the movable jaw, but only to press forward the wedge E to advance its foot 30 between the pin 25 and the leaf spring D. By so doing the spring D is depressed sufficiently to dis-

engage the slidable jaw from the frame back, thereby permitting free longitudinal movements thereof to any desired position. When pressure is released upon the wedge, the 5 movable jaw is immediately locked for further service. It is obvious, of course, that the movable jaw may be shifted toward the other simply by the application of pressure upon its end, and without the necessity for 10 any pressure upon the wedge.

The wrench of this invention, it will be noted, is characterized by certain features of novelty which include means for holding the slidable jaw in engagement with the 15 frame, and wedge means for retracting the spring to permit free longitudinal movements of the slidable jaw as required. It may be constructed in forms other than the one herein shown and described, but in so 20 far as any such modifications make use of the improvements which are defined in the appended claims, I desire that they be included within the scope of this patent.

I claim:

25 1. In a wrench, the combination of a handle provided with a fixed jaw, a U-shaped frame mounted on the handle and provided with ratchet teeth which face the handle in spaced relation thereto, a jaw movably 30 arranged within the frame and provided with ratchet teeth adapted to coöperate with those in the frame, a leaf spring carried by the handle and pressing on the movable jaw to maintain its ratchet teeth in engagement 35 with those in the frame, a pin arranged transversely in the frame, and a wedge arranged for projection between the pin and leaf spring to depress the latter whereby the movable jaw may be freely moved within 40 the frame, substantially as described.

2. In a wrench, the combination of a handle provided with a fixed jaw, a frame mounted thereon and provided with teeth therein, a movable jaw mounted to shift both 45 lengthwise and laterally of the handle, means carried by the movable jaw adapted when the latter is shifted laterally to one position to engage the frame teeth whereby the movable handle is held in a fixed position of adjustment longitudinally of the 50 wrench, tension means for normally maintaining the movable jaw in the aforesaid position, and a wedge adapted to counteract the tension means whereby the movable jaw 55 is free to shift to another position prelimi-

nary to movement longitudinally of the wrench, substantially as described.

3. In a wrench, the combination of a handle provided with a fixed jaw, a movable jaw mounted to shift both lengthwise and laterally of the handle, means within which the movable jaw is resiliently mounted having ratchet teeth adapted to engage with the jaw for holding the same in a fixed position of adjustment, a wedge slidably arranged 60 on the handle and adapted when advanced to permit the movable jaw to freely shift laterally whereby it may also shift longitudinally of the wrench, and spring means normally tending to hold the wedge in retracted position, substantially as described. 65

4. In a wrench, the combination of a handle provided with a fixed jaw, a frame carried by the handle, a movable jaw arranged within the frame and adapted to be shifted lengthwise of the handle, a coiled spring arranged between the handle and movable jaw tending to hold the latter remote therefrom, coöoperating ratchet teeth formed on the movable jaw and frame whereby the former is held in a fixed position of adjustment within the latter, means interposed between the coil spring and the movable jaw and having one end anchored to the handle, and means for depressing the said means against 85 the tension of the coiled spring to thereby release the movable jaw from engagement with the teeth of the frame, substantially as described. 70

5. In a wrench, the combination of a handle provided with a fixed jaw, a frame carried by the handle, a movable jaw arranged within the frame, spring means arranged between the handle and movable jaw tending to hold the latter away from the former, interengaging means formed on the movable jaw and frame adapted to retain the former in a selected position of adjustment within the latter when the jaw is held away from the handle, a wedge interposed 90 between the handle and movable jaw and normally held in retracted position, and means interposed between the spring means and movable jaw with which the wedge may coöperate to depress the former whereby the movable jaw is free to be shifted within the frame, substantially as described. 95

100 AUGUST S. LIZAK.
